[57] ABSTRACT

Tin salts formed by the reaction of di lower alkyl or aryl

tin oxides and dimercapto ethyl formal and similar dimercapto compounds of the general formula

wherein R is $-(\text{CH}_2)_m(\text{OCH}_2)_s-\text{O}-[\text{CH}_2]_m-$
 $-\text{O}(\text{CH}_2)_p-\text{O}-[\text{CH}_2]_n-$ wherein p is 0 or 1, m is 2 to about 6 and n is 0 to about 6 and R' is lower alkyl of up to about 10 carbon atoms, or carbocyclic aryl containing one or two aromatic rings when combined with conventional tin based stabilizers show a synergistic light and heat stabilizing effect in poly(vinyl chloride) polymers.
